UNITED STATES PATENT OFFICE.

ISAIAH L. ROBERTS, OF NEW YORK, N. Y., ASSIGNOR TO ROBERTS CHEMICAL COMPANY, OF NEW YORK, N. Y., A CORPORATION OF NEW YORK.

ELECTROLYTIC DIAPHRAGM.

No. 831,474.

Specification of Letters Patent.

Patented Sept. 18, 1906.

Application filed December 23, 1904. Renewed August 27, 1906. Serial No. 332,099.

To all, whom it may concern:

Be it known that I, ISAIAH L. ROBERTS, a citizen of the United States, residing at New York, in the county of Kings and State of New York, have invented certain new and useful Improvements in Electrolytic Diaphragms, of which the following is a specification, reference being had to the drawings accompanying and forming part of the same.

In several prior patents, particularly Nos. 422,333, 522,614, 522,616, 522,617, and 522,618, I have described electrolytic diaphragms which are of such nature as to allow electrolytic action to take place through the same, but at the same time preventing transfusion or physical commingling of the liquids which are separated by the diaphragm or at most permitting such transfusion only to a practically negligible degree. The materials employed in the diaphragms are largely plastic, and therefore have to be confined in the form desired by a suitable holder. The latter is usually made of cloth, which is in turn supported by a stiff framework of a suitable kind, such as a basket of wire-gauze. It is to the improvement of diaphragms of this general type, which possess great utility in various electrolytic arts, that the present invention is directed.

One of the objects of my invention is to provide a diaphragm in which at least one of the supporting fabrics or faces shall possess to a degree at least the properties of the plastic material—that is, allowing electrolysis to take place therethrough, but at the same time preventing transfusion during the passage of the current—thereby making the support of the plastic material actually a part of the effective separating medium. Less of the plastic or gelatinous material is therefore needed for a given purpose or, stated otherwise, the effectiveness of a given diaphragm is increased by this construction. It is also desirable that the surface of the diaphragm be straight and smooth, free from wrinkling or bulging. This is a condition which it is difficult if not practically impossible to secure where flexible supports, such as sheets of cloth, are used, and it is therefore a further object of my invention to provide a support which shall be at least sufficiently rigid to prevent stretching, bulging, or other distortion. The support should also be indestruc-

table in the liquids with which it comes in contact, a characteristic which it is impossible to secure completely with supports made of cloth or other organic material.

A further object of my invention is therefore to provide a support which will be practically unaffected by the electrolytic liquids, particularly on the anode side of the diaphragm, and therefore have longer life than the diaphragms previously used. The material which has been found to best meet these various requirements is a composition of asbestos and magnesium silicate. Such compositions are common in the market, known as "transite," "magnesia building lumber," &c., and their manufacture therefore need not be described in detail. Such material, of the desired thickness, possesses the necessary degree of porosity, is flexible enough to bend without fracture, and is but slightly affected by the original liquids of the bath or by those resulting from the electrolysis.

Another object of my invention is to provide an electrolytic cell or apparatus of novel form wherein the properties of the diaphragm described may be effectively utilized.

To these and other ends the invention consists of the novel features, arrangements of parts, and combinations of elements herein-after described, and more particularly pointed out in the claims.

Referring now to the drawings, Figure 1 shows in vertical section a cylindrical cell embodying my improvements, and Fig. 2 is a horizontal section of a rectangular structure containing a number of cells with a common diaphragm.

In the cell shown in Fig. 1, 1 is a cup or basket of wire-gauze strengthened at top and bottom by metal rings 2 3. Inside of the basket is a cloth bag or lining 4, within which is a layer of the plastic or gelatinous material 5. In setting up the cell I prefer to place first on the bottom of the cloth-lined basket a layer of the plastic material, as 6, then on this a disk 7 of the asbestos-magnesia composition. The disk is pressed down upon the viscous material until the two are in close contact, leaving the gelatinous or viscous layer of the desired thickness, generally equal to or slightly greater than the space which separates the edge of the disk from the sides of the bag. On the disk is now placed a cylind-

der or tube 8, made of the composition, the diameter of which is about the same as that of the disk, preferably slightly smaller. The space between the cylinder and the bag is now 5 evenly packed with the plastic material, as shown. The diaphragm is then complete and ready for use. In Fig. 1 it is shown suspended in an iron vessel or tank 9, which constitutes the cathode, the anode being located inside 10 the diaphragm-cup, as indicated at 10. The asbestos-magnesia cup may be made in one piece if desired; but the disk and cylinder construction described is cheaper and more convenient in some respects.

15 In Fig. 2 the tank is made of wood, with the diaphragm in the form of a flat plate extending longitudinally therethrough. The tank is divided into the desired number of cells by strips of slate, paraffined wood, or 20 other material, as 11. That part of the diaphragm which is composed of the asbestos-magnesia composition is indicated by 12. Spaced apart therefrom by strips 13 is a sheet 25 of cloth 14, the space thus left being packed with the plastic non-porous material 15. By means of tie-bolts 16, passing through the ends of the side walls 17, the parts may be brought as firmly together as desired, as will be readily understood. The anodes are indicated by 18 and the cathodes by 19. In 30 this form it will be seen that no wire support for the cloth side of the diaphragm is necessary.

It is obvious that in both the forms illustrated the cathode side of the diaphragm 35 may also be formed of the asbestos-magnesia

composition; but in most cases this will not be found necessary.

The specific forms herein described are of course only typical of my invention, which 40 may be variously embodied without departure from its proper scope. It will also be understood that where I have used the term "rigid body" I do not mean that the same must be absolutely inflexible, but merely that 45 it should be at least stiff enough to stand its ordinary usage without distortion.

The term "non-porous" used to describe the plastic or other material on the rigid body is not to be understood to mean that the material referred to must necessarily be totally 50 impervious, but rather that it may permit substantially no transfusion or physical commingling of the liquids separated by the diaphragm.

55 What I claim is—

1. An electrolytic diaphragm comprising a rigid body of porous material, a layer of non-porous material thereon, and a fabric on the non-porous material to retain the same on the 60 rigid body, as set forth,

2. An electrolytic diaphragm comprising a rigid body of porous material, a layer of non-porous material thereon, a fabric on the non-porous material to retain the same on the rigid 65 body, and a reticulated support for the fabric, as set forth.

ISAIAH L. ROBERTS.
